United States Patent Office

Des. 227,503
Patented June 26, 1973

227,503

MOBILE PHOTOCOPY CAMERA UNIT

Gary E. Raymond, P.O. Box 531, Kenvil, N.J. 07847

Filed Oct. 20, 1971, Ser. No. 190,964

Term of patent 14 years

Int. Cl. D16—03

U.S. Cl. D61—1 Q

FIG. 1

FIG. 2

FIG. 1 is a rear and right side isometric view of a mobile photocopy camera unit, showing my new design;

FIG. 2 is a front and right side isometric view thereof with the copy holder in a raised position; the left side being substantially a mirror image thereto.

I claim:

The ornamental design for a mobile photocopy camera unit, as shown and described.
